UNITED STATES PATENT OFFICE.

AMOS WHITTEMORE, OF CAMBRIDGEPORT, MASSACHUSETTS.

IMPROVEMENT IN STREET-RAILWAY TURN-OUTS.

Specification forming part of Letters Patent No. **177,603**, dated May 16, 1876; application filed November 20, 1875.

To all whom it may concern:

Be it known that I, AMOS WHITTEMORE, of Cambridgeport, in the county of Middlesex and State of Massachusetts, have invented a new and valuable Improvement in Horse-Car-Rail Switch; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of my switch, and Figs. 2 and 3 transverse sectional views of the rail thereof.

This invention has relation to horse-car railroads; and the nature of my invention consists in a novel arrangement of guard-flanges with relation to sections of the track-rails where there are sidings or turn-outs from the main rails, as will be hereinafter explained.

It is a very common occurrence for street-cars to leave the track in switching from a main track to a side track, and vice versa, and the object of my invention is to obviate this source of trouble.

In the annexed drawing, A A designate the straight main-track rails, and B B designate the turn-out or siding rails branching off from the main-track rails. The sections between the main rails and the turn-out rails have

flanges C C' formed on them, which are on the outside of, and extend above, the rolling-surfaces of their respective rail-sections. The guard-flange C is about the center of the main turn-out rail, and extends along the entire distance where the wheels are liable to "jump" the rail while the driver is turning his car from the main track to the side or branch track. Should there be a tendency at such point for the wheels to jump the track the outside of the right-hand wheels will strike the guard-flange C and prevent displacement of the car. The guard-flange C' on the main-track rail is so arranged with relation to the siding that it will resist any tendency of a car jumping the track in passing from the siding upon the main track.

In practice each switch-section with its flange will be cast entire.

What I claim as new, and desire to secure by Letters Patent, is—

Guard-flanges C C', arranged in the relation to each other and to the siding or turn-out, substantially as described.

In testimony that I claim the above I have hereunto subscribed my name in the presence of two witnesses.

AMOS WHITTEMORE.

Witnesses:
